UNITED STATES PATENT OFFICE

CHARLES FISHER, OF NEWARK, NEW JERSEY, ASSIGNOR TO THE AUTOMATIC RECORDING SAFE COMPANY, OF CHICAGO, ILLINOIS, A CORPORATION OF ILLINOIS

SAVINGS BANK

Application filed September 17, 1927. Serial No. 220,222.

This invention relates particularly to savings banks having a form simulating a book; and the primary object of the invention is to provide a thoroughly practicable construction which can be manufactured easily and at small cost and which is staunch and reliable.

The invention is illustrated in its preferred embodiment in the accompanying drawings, 10 in which—

Fig. 1 is a perspective view of a savings bank embodying the invention; Fig. 2 a plan sectional view on an enlarged scale; Fig. 3, a transverse section taken as indicated at 15 line 3 of Fig. 2; Fig. 4, a broken sectional view showing a detail; Fig. 5, a perspective view of the main part of the casing before the covering has been applied thereto; Fig. 6, a perspective view of the removable closure which in the assembled structure corresponds with the edges of the leaves of a book; Fig. 7, a sectional view on an enlarged scale taken as indicated at line 7 of 20 Fig. 6; Fig. 8, an edge view of the reciprocal cable bolt, or locking-bar; Fig. 9, a section taken as indicated at line 9 of Fig. 8, but showing the locking-bar in its relation to the closure in which it is mounted; Fig. 10, a broken plan sectional view showing a modification; and Fig. 11, a broken sectional view taken as indicated at line 11 of Fig. 10.

Referring to Figs. 1-9, A designates the main body of the casing which corresponds with the sides and back of a book; B designates a removable closure which corresponds with the edges of the leaves of a book; and C designates a bolt, or locking-bar, slidably mounted in the closure B.

The body A of the casing comprises a sheet 40 of suitable material, preferably a thin sheet of hard fibre which is so formed as to provide a back 1 and sides 1^a; plates 2 disposed adjacent the inner surfaces of the sides 1^a; and spacing-posts 3 uniting the sides 1^a and inner plates 2 in the manner shown in Fig. 4. As there shown, the posts are tubular and have reduced end-portions 3^a extending through perforations in the side-members and plates and spun, or riveted, at the outer surfaces of 45 the plates. The posts thus have shoulders at

3^b which bear against the inner surfaces of the plates 2. The plates 2 may be of hard fibre, if desired.

The plates 2 serve to reinforce the side-walls of the body A. They are of smaller 55 dimensions than the side-walls, or plates, of the body A, and their end edges 4 are adapted to serve as guides for the closure in the assembling operation.

The body A preferably has applied thereto a covering 5 of suitable fabric, such as cloth, paper, leather, or the like; and preferably pads 6 are introduced between the covering and the side-walls of the casing. The margins 5^a of the covering are turned in 60 about the edges of the U-shaped body of the casing and cemented to the inner surfaces, 65 as will be understood from Fig. 3.

The plates 2 of the casing are connected by guard-studs 7 which are disposed a little 70 back of the front end-posts 3.

The closure B is of U-form, having the longitudinal edge-member 8 and end-members 8^a, as shown in Fig. 6. The U-shape closure is of channel-form cross-section and its longitudinal member 8 houses the slideable locking-bar C. Both of these parts preferably are made of strips of sheet brass stamped into suitable form, and the outer surface of the closure is in practice given a finish resembling the gilt edges of the leaves of a book. 75

The locking-bolt C comprises a strip which has its intermediate portion struck up or embossed to provide a wall 9 and flanges 9^a. The flanges 9^a are turned towards the main 80 wall of the member 8 of the closure. Near the ends, the locking-bar is flattened as indicated at 9^b, and the extremities are turned 85 backwardly as indicated at 9^c, and then at right angle thereto as indicated at 9^d. The points 9^d extend in the same direction and afford hooks which are adapted to engage the front end-posts 3. The flattened portions 9^b are confined between guide-posts 10 and the 90 main wall of the member 8 of the closure, as will be seen from Figs. 2 and 8. A spring 11 serves to throw the locking-bar to locking position. This spring has an end-portion 11^a secured to one flange of the closure by means 95 of a lug 12 which is struck from the flange 100

and clenched upon the spring. The other end of the spring bears against the shoulder 13 of the locking-bar. One flange of the member C is cut away as indicated at 14 to permit clearance for the spring. The same flange is provided with a recess 15 which affords a shoulder 15^a adapted to be engaged by a key when it is desired to retract the locking-bolt against the force of the spring 5 as will be understood from Fig. 9.

10 A key barrel 16 is rotatably confined between the member C and the main wall of the member 8 of the closure.

One of the end-members 8^a of the closure is 15 provided with a coin-slot 17 which is equipped with a slot-guard 17^a which need not be described in detail. Adjacent the coin-slot is a perforation 18 through which bills may be introduced.

20 It will be noted from Fig. 2 that the members, or posts, 7 serve to guard the hook-portions 9^a of the locking-bar against tampering, as by inserting an implement through the coin-slot 17, or bill-hole 18.

25 The coin-slot device includes a plate 19 which is provided with a slot and which is secured in position by means of clenching lugs 20 formed integrally with the member 8^a. The plate 19 is equipped at one end with an 30 inwardly extending piece 19^a which serves as a guard adapted to prevent coins from getting back of the adjacent end of the locking-bar. The portion 9^a of the locking-bar is provided with a slot 21 through which the projection 35 19^a may extend when the locking-bar is retracted.

The locking-bolt C is provided at an intermediate point with laterally extending lugs 22 which are engaged by lugs 23 struck inwardly from the flanges of the members 8 of the closure. These lugs serve as guide-lugs 40 and prevent the locking-bar from being sprung inwardly away from the main wall of the member 8.

45 In the modification shown in Figs. 10 and 11, the construction is the same as described previously and corresponding parts are given corresponding reference characters.

In this case, the inner plates, designated 50 2^a, which correspond with the plates 2 shown in Fig. 3, have their marginal portions struck away from the side-walls 1^a of the casing, thus providing guide-flanges 2^b which are adapted to interlock with the flanges of 55 the closure B. In this modification, the reinforcing plates 2^a preferably are of metal.

The construction described is simple, easily manufactured, durable, and the product presents an exceedingly neat appearance. The 60 guard-posts 7 prevent the unauthorized manipulation of the locking-bar, as by means of a button-hook, or other implement, through the coin-slot 17, or bill-hole 18.

65 It may be added that the edges of the internal reinforcing plates 2 not only afford guides

for the closure, but they also serve as obstructions adapted to prevent the insertion of an implement for the purpose of springing the casing to enable coins to be abstracted from the savings bank.

70 The foregoing detailed description has been given for clearness of understanding only, and no unnecessary limitations should be understood therefrom.

What I regard as new, and desire to secure 75 by Letters Patent, is:

1. A book-form savings bank comprising a U-shape casing having its side-walls equipped at their inner surfaces with reinforcing plates whose edges afford guide-shoulders, spacing-posts interposed between said plates and having their end-portions secured to the side-walls of the casing, and a U-shape closure embracing the edges of 80 said reinforcing plates and simulating the edges of the leaves of a book, said closure being equipped with a coin-slot and being equipped also with a locking-member engaging said posts.

2. A book-form safe comprising a U-shape casing-member, reinforcing plates adjacent the inner surfaces of the side-walls of said casing-member and of smaller dimension than said side-walls, the end edges of said plates affording guide-shoulders, posts connecting said side-walls and plates and extending across the intervening space between the plates, U-form closure having inturned flanges engaging the guide-shoulders of said plates, a coin-slot device associated with one of the end-members of said closure, and a 85 sliding locking-bar housed in the longitudinal member of said closure and equipped at its extremities with hooks extending in a common direction and engaging the adjacent 90 posts.

3. A book-form safe comprising a U-shape casing-member, posts connecting the side-walls of said member, a U-shape closure simulating the edges of the leaves of a book 110 and of channel cross-section, a coin-slot device associated with an end-member of said closure, a sliding locking-bar housed in the longitudinal member of said closure and equipped with hooks extending in a common direction and engaging corresponding 115 posts, and a guard-member adjacent one end of said coin-slot adapted to prevent coins from lodging back of the adjacent end-portion of the locking-bar.

4. A book-form safe comprising a U-shape casing-member, posts connecting the side-walls of said casing-member, a U-shape closure having one end-member equipped with a coin-slot device, a locking-bar slidably mounted in the longitudinal member of said closure and equipped with hooks extending in the same direction and engaging adjacent 125 posts, and posts back of and guarding said hooks.

5. A U-shape closure for a book-form safe, said closure being of channel-form cross-section and having one end-member equipped with a coin-slot device, guide-posts connecting the flanges of the longitudinal member 5 of said closure, a locking-bar housed between said flanges and having guide-portions confined between said posts and the main wall of said longitudinal member, the end-portions of said locking-bar being equipped 10 with hooks extending in a common direction and the intermediate portion of said locking-bar being spaced from the main wall of said longitudinal member and equipped with laterally extending guide-lugs, guide projections struck inwardly from the flanges of 15 said longitudinal member and engaging said guide-lugs, a spring housed between said locking-bar and the main wall of said longitudinal member and serving normally to hold the locking-bar in the locking position, and a key-barrel housed between said locking-bar and said main wall and having a portion journalled in said main wall.
